VIBRATORY MOTOR HOUSING AND FRAME UNIT

Verlan L. Downing, Seattle, Wash.

Application January 28, 1959, Serial No. 54,367

Term of patent 14 years

(Cl. D55—1)

Figure 1 is a top perspective view of the vibratory motor housing and frame unit showing my design.

Figure 2 is a side view thereof.

Figure 3 is an end view thereof.

Figure 4 is a bottom view thereof.

I claim:

The ornamental design for a vibratory motor housing and frame unit, substantially as shown.
